MICHAEL SEDLMEIR, OF MULHEIM-RUHR, GERMANY, ASSIGNOR TO HOLZWARTH GAS TURBINE CO., OF SAN FRANCISCO, CALIFORNIA, A CORPORATION OF DELAWARE

NOZZLE FOR COMBUSTION-GAS TURBINES

Application filed March 29, 1927. Serial No. 179,247.

My present invention relates to nozzles for combustion gas turbines, and has for its object to construct nozzles of this type in such a manner as to obtain a sturdy and durable article and to facilitate the manufacture, finishing, cleaning, and cooling of the nozzle.

A preferred and satisfactory embodiment of my invention is illustrated by the accompanying drawings, in which Fig. 1 is a longitudinal section of the improved nozzle, with an indication of the adjacent parts of the apparatus; Fig. 2 is a face view, looking in the direction of the arrow 2 in Fig. 1; Figs. 3, 4 and 5 are sections on lines 3—3, 4—4, and 5—5, respectively of Fig. 1; and Fig. 6 shows a modification of the nozzle outlet shown in Fig. 2.

In Fig. 1 I have indicated diagrammatically certain parts of a turbine of the Holzwarth type, viz.: a combustion chamber 10 from which combustion gases under pressure pass through an outlet controlled by a valve 11 into a conduit 12 which delivers such gases into the tapering inlet portion 13' of my improved nozzle 13. The outlet of this nozzle is adjacent to the path of blades 14 carried by the rotor 15, the axis of which would be a horizontal line in a view such as Fig. 1. It will be understood that while I have shown my improved nozzle in conjunction with parts of the type indicated at 10, 11, 12, 14, 15, and while my invention has been devised primarily for use in conjunction with a turbine and combustion chamber construction of this type, I do not wish to restrict myself thereto.

From its narrowest portion or throat 13'' the passage of the nozzle 13 flares toward its outlet. The body of the nozzle, in which said passage is formed, is cast in one piece of Monel metal or other suitable material able to perform its functions satisfactorily at the high temperatures to which the nozzle is exposed. Monel metal also has the advantage that it is not oxidizable, and is readily worked, polished, and welded.

The jacket for the water or other medium employed for cooling the nozzle is formed partly by outer walls such as 13^a and 13^b cast

integral with the nozzle body, at the inlet and outlet ends thereof, and partly by a shell 16 made of pieces of Monel sheet metal welded to the said walls 13^a, 13^b. This construction provides an easily made casting and (before applying the shell 16) the inner walls of the jacket can be cleaned thoroughly, thus insuring a proper contact of the water, oil or other cooling medium, with such walls.

The cooling medium enters through an opening 17 near the outlet of the nozzle, then passes through a jacket chamber 18 the upper boundary of which is formed by an external surrounding rib 19 on the nozzle body, and then through an aperture 19' in said rib into an annular chamber 18' lying between the rib 19 and a similar rib 20 nearer to the nozzle inlet. At a point preferably diametrically opposite to the aperture 19', the rib 20 has an opening 20' through which the cooling medium enters a third jacket chamber, 18'', adjacent to the throat of the nozzle. From this chamber the cooling medium passes out through an opening 21.

I have found that in practice, in order to secure the best results, no point of the surface with which the combustion gases come in contact should be farther away than about two inches from the nearest point of the surface with which the cooling medium is in contact. For this reason the tip of the nozzle has been notched or cut off, as indicated at 22. This cut-off portion might be made with a straight vertical edge or line, or a curve or arc shape might be adopted as shown at 22^a in Fig. 6. At the lower portion of the outlet, a sharp edge 23 has been provided in order that the stream of combustion gases may not be bent at this point toward the nozzle, but continue in a straight line.

At the inlet end of the nozzle I prefer to leave a recess which is subsequently closed by a filling piece 24 secured in position by bolts 25. The purpose of this recess is to allow easier access to the inner surface of the nozzle so that it may be smoothed or otherwise finished more readily. After this finishing operation, the filling piece 24 is se-

cured in position and the entire nozzle fastened to the conduit 12 in any suitable manner.

As shown in Fig. 2, the longitudinal axis 5 of the main portion of the nozzle is tangential at the part 22 of the nozzle outlet to the median circle indicating the center of the arcuate nozzle outlet. The center of curvature of this nozzle outlet is upon the axis of 10 the turbine rotor, which latter has not been illustrated in this case.

Various changes in the specific form shown and described may be made within the scope of the claims without departing from the 15 spirit of my invention.

For instance the shell need not be of the same material as the nozzle body, but can be made from copper being applied to the nozzle body by electrocoppering the nozzle body. While electroplating, the jacket 20 should be filled with a suitable material like wax, which is molten and removed, when the thickness of the electrocopper shell is sufficiently strong.

25 I claim:

1. A nozzle for conducting combustion gases under pressure to the rotor of a turbine, comprising a body having an inlet flange whose surface is perpendicular to the 30 axis of the turbine, said body including a section whose axis is substantially parallel to the axis of the turbine and which terminates in a constricted portion, and a second section whose axis is inclined to the axis of 35 the turbine and increasing in cross-sectional area from said constricted portion to the discharge end of said nozzle, said body being double-walled at both its inlet and discharge ends and single-walled at the middle thereof, 40 and a separate shell surrounding the nozzle body at said single-walled middle portion thereof and connecting the outer walls of said double-walled portions.

2. A nozzle for conducting combustion 45 gases under pressure to the rotor of a turbine, comprising a body having an inlet flange whose surface is perpendicular to the axis of the turbine, said body including a section whose axis is substantially parallel to 50 the axis of the turbine and which terminates in a constricted portion, and a second section whose axis is inclined to the axis of the turbine and increasing in cross-sectional 55 area from said constricted portion to the discharge end of said nozzle, said body being double-walled at both its inlet and discharge ends and single-walled at the middle thereof, and a separate shell surrounding the nozzle body at said single-walled middle portion thereof and connecting the outer walls of 60 said double-walled portions, said body being provided with external ribs at said single-walled middle portion and said shell 65 surrounding said nozzle body in contact with

said ribs whereby a jacket having a plurality of passages is formed.

3. A nozzle for conducting combustion gases under pressure to the rotor of a turbine, comprising a body having an inlet section terminating in a constricted portion, and a second section whose axis is oblique to that of said inlet section, said second section increasing in cross-sectional area from said constricted portion toward the discharge end 70 of the nozzle, said body being double walled, at both its inlet and discharge ends and single walled at the middle thereof, and a separate shell surrounding the nozzle body at said single-walled middle portion and connecting the outer walls of said double-walled portions.

4. A nozzle for conducting combustion gases to the rotor of a turbine, comprising a body having an inlet section and an outlet section, the axis of said outlet section being inclined to the axis of said inlet section, said body being of constricted cross-section intermediate its ends and increasing in cross-sectional area from such constriction toward 90 the outlet end of the nozzle, said body being double-walled over portions thereof adjoining its inlet and outlet ends and single-walled intermediate such double-walled portions, and a separate shell surrounding the 95 nozzle body at said single-walled intermediate portion and connecting the outer walls of said double-walled portions.

In testimony whereof I have hereunto set my hand.

MICHAEL SEDLMEIR.
